UNITED STATES PATENT OFFICE.

STATES LEE LEBBY, OF CORNING, NEW YORK.

PHOTOGRAPHIC-PRINTING APPARATUS.

Application filed December 18, 1928. Serial No. 607,845.

The prime object of the invention is to provide a novel electric circuit for photographic printing apparatus, the circuit being so arranged that the lamps of the apparatus will be protected from so called burn-outs resulting from constant relighting in making the exposures to the prints.

In the accompanying drawing wherein is illustrated the preferred embodiment of my invention; the figure is a horizontal section through the photographic printing apparatus with the top removed and showing the lighting circuit when the apparatus is ready to make exposures.

15 The apparatus comprises a rectangular box 5, which may be of any convenient size. In the center of one end wall 6, of the box, I secure an ordinary socket 7, while near one end of one of the sides 8 of the box, I secure another socket 9. By preference the socket 7 carries a high candlepower exposure lamp 10, while the socket 9 carries a low candle-power ruby lamp 11, the lamp 11 having about one fourth the candlepower of the lamp 10, as is generally the practice in apparatus of this character.

Conductors 12 and 13 entering the side 6 of the box 5 from the exterior, are respectively connected to the sockets 7 and 9. Connecting the socket 7 to the socket 9 is another conductor 14. This arrangement of the light circuit is such that the lamps 10 and 11 are connected in series, and will both be simultaneously supplied with current 25 from the conductors 12 and 13. A switch 15 can be secured to the conductors 12 and 13 beyond the box to serve as means of breaking the circuit when the apparatus is not in use, or the usual attachment cord and plug 40 may be used instead.

When the apparatus is connected to the circuit for use, the ruby lamp 11 will burn at nearly normal brilliancy and the current, which is also passing through the exposure lamp 10 will keep the filament of the latter at a glow, or warmed up.

Now in order to short circuit the ruby lamp 11 and allow the full line voltage to pass through the exposure lamp 10, I utilize 45 a simple push-button switch 16 which has one terminal connected to the conductor 14, between the sockets 7 and 9, by means of a conductor 17, and its other terminal connected to the conductor 13, by means of a

conductor 18. This push-button may be actuated by being manually depressed.

When the apparatus is in use and assuming that the operator is positioning a negative and sensitized paper in the printing frame (not shown), the current of the full line voltage, will, in passing through the circuit, impart a slight glow to the filament of the exposure lamp 10. This glow is hardly noticeable to the eye, and hence will not be of sufficient brilliancy to prove detrimental to the proper functioning of the apparatus, while the filament of the ruby lamp 11 will burn at nearly normal brilliancy.

Assuming that the operator wishes to make an exposure, the push-button 16, upon being depressed, will cause the lamp 11 to be short-circuited, thereby increasing the current to lamp 10, and thus bring the lamp 10 to full brilliancy.

Upon releasing the push-button 16, the filament of the exposure lamp 10 gradually drops in temperature and thus decreasing in resistance, gradually brings the ruby lamp 11 back to nearly normal candlepower. At the same time the small amount of voltage 75 retained by the exposure lamp 10 from the ruby lamp 11, for keeping the filament of lamp 10 warmed up, further increases the life of the ruby lamp 11.

Thus this method of relighting the ruby 85 lamp 11, provides what may be termed, an automatic heat rheostat in lamp 10, which at the moment of releasing the push-button 16, gradually de-energizes, and in cooling, gradually lowers in resistance, forcing its 90 voltage to the lamp 11 which is the higher resistance unit of the circuit.

Heretofore, so far as I am aware, it has been the custom to provide independent switches, or a double-throw switch for the 95 lamps. That is to say, the apparatus now in general use are composed of two electric circuits, the exposure lamps being on one circuit, while the safe light, or ruby lamp is on the other circuit, it being necessary for the 100 operator to switch from one circuit to the other, when making consecutive exposures.

This constant switching on of electric incandescent lamps produces a sudden rise in the temperature of the cold lamp that tends 105 to fracture or burn out the filament, due to the very sudden expansion of the several brittle parts thereof, and it has been proven

that it is generally the case that incandescent lamps burn out at the moment of lighting.

Thus by my invention the high candle-power exposure lamps and the low candle-power ruby lamps are controllable from a single push-button switch, which is so arranged with respect to the light circuit that the function of both lamps are controlled thereby. Furthermore, the filaments of both lamps will at all times be protected from sudden thrusts of the entire line voltage, and therefore the loss of the lamps through burn-outs is overcome.

Having thus described my invention what I claim is:

A device of the class described comprising an electric circuit having two lamps, one of

said lamps being clear and the other lamp being ruby, said ruby lamp having relatively greater resistance than the clear lamp and being capable of carrying sufficient current to cause subdued illumination of the clear lamp, a switch, and circuit connections for connecting the source of current, and the switch in parallel with the ruby lamp, whereby the ruby lamp can be short circuited to allow the full line voltage to pass through the clear lamp and the clear lamp can function as an automatic heat rheostat when the ruby lamp is lighted.

In testimony whereof, I hereunto sign my name.

STATE LEE LEBBY.
